Los Angeles, Calif.

Application April 29, 1937, Serial No. 139,675

10 Claims.

(Cl. 4—148)

This invention relates to combination fixtures, and more particularly to a combination fixture adapted for use in connection with shower and tub installations or similar spout and spray installations.

This invention is particularly related to an improvement over the combination spout and spray fixture set forth in the Myron J. Glauber Patent No. 1,653,956, granted December 27, 1937.

10 It is an object of this invention to provide a combination spout and spray fixture wherein there is provided a means for controlling the direction of flow of water, either to the spout or the spray, in which means there is included a fixture formed as an integral casting, including a pair of outlets and a single inlet wherein the direction of flow from the inlet to the outlets is controlled through a pair of orifices forming a dividing plate between the said outlets.

20 Another object of this invention is to provide a combination fixture wherein there is included an ejector means formed as an orifice within a fitting and which is operable in connection with a valve member to control the flow of water in the combination fixture.

Other objects and advantages of this invention it is believed will be apparent from the following detailed description of a preferred embodiment thereof as illustrated in the accompanying drawings.

30 In the drawings:

Figure 1 indicates a side elevation partly in vertical section of a combination spout and spray installation embodying our invention.

35 Figure 2 is a front elevation of the installation embodying our invention.

Figure 3 is a sectional elevation on an enlarged scale of a unitary connecting fixture embodied in our invention.

40 Figure 4 is a modified form of construction embodied in our invention, partly in vertical section.

Figure 5 is an elevation of a further modified form of construction embodying our invention 45 likewise partly in vertical section.

In the preferred embodiment of our invention as illustrated in the accompanying drawings, 1 indicates a cold water conduit and 2 a hot water conduit. The flow of water through the conduits 1 and 2 is controlled by cold and hot water control valves 3 and 4. The conduits 1 and 2, after leaving the valves 3 and 4 are connected by a coupling 5 in which the hot and cold water may be mixed. Connected with the coupling 5 is a pipe 55 6 which is connected with the inlet 7 of the con-

necting fitting 8. The fitting 8 has a spout outlet 9 and a spray or shower outlet 10. A spout 11 is mounted directly in the outlet 9. Mounted in spout 11 is a valve 12. Connected with the outlet 10 is a pipe 13 which extends upwardly and is 5 connected to the spray or shower head 14.

The fitting 8 is of unitary cast construction and includes an orificed dividing plate 15 including a spout orifice 16 and a spray orifice 17.

The mode of operation of the fixture embodying our invention is: Water as admitted from the hot and cold water pipes 1 and 2, mixed in the member 5, is conducted to the inlet 7 of the unitary cast connecting member 8. The water normally passes outward through the spout orifice 15 16 and through the spout 11 and is delivered into the bathtub, lavatory, or other plumbing fixture. The valve 12 is moved to open position during this operation. When it is desired to stop the flow of water from the spout 11 to cause the water 20 to flow from the spray or shower head 14, the valve 12 is moved to a closed position. This causes the water to back up and flow through the orifice 16 and back through the orifice 17 up through the pipe 13 and out a spray head 14. When the 25 valve 12 is opened, water is normally prevented from flowing in this direction due to the fact that the water issuing through the orifice 16 produces an ejector action in the spout 11 causing air to be drawn through the spray 14, pipe 13, and outlet 10. 30

In the modification of our invention as particularly illustrated in Figure 3, in order to permit in the roughing-in operations either the conduit 6 or 13 as may be most convenient to be 35 used as the inlet while the opposite of said conduits is to be used as the connection extending to the shower head 14, the restrictions 16 and 17 are formed whereby irrespective of which of said conduits may be used as the inlet conduit, 40 there is provided a restriction in said inlet so that an ejector action will be obtained whereby the desired direction of flow of the water may at all times be had. The restrictions as thus provided by the ports 16 and 17 formed in the partition 45 15 provide for the maintaining of an ejector action in the coupling irrespective of which branch is utilized as the inlet.

In the modified form of our invention as illustrated in Figure 4, similar parts have been designated by a similar numeral with the addition of an exponent "a" thereto. In this form of our invention the coupling 5a is formed with two outlets normally the spout outlet 9a, shower outlet 10a and a single inlet 7a. Conduits 6a, 13a 55

and the spout 11^a are connected in the same manner as set forth in connection with the modification of our invention as illustrated in Figures 1 to 3, inclusive.

5 In this form of our invention the restrictions which provide for the ejector action are provided by forming restricted passages 16^a and 17^a directly in the inlet 7^a or outlet 10^a. As in the case of the modification illustrated in Figures 1 to 3, the inlet and outlet divided between the conduits 13^a and 6^a may be reversed where in the roughing-in operation it becomes desirable.

10 In the modification of our invention illustrated in Figure 5, similar parts have been designated by a similar numeral with the addition of an exponent "b" thereto. In this modification of our invention illustrated in Figure 5, the conduit 13^b extends directly to the shower head. A conduit 11^b extends to, or is connected with, the bathtub spout. In this modification the connecting member 5^b is formed as a cross. A hot water supply pipe 1^b, in which the valve 3^b is mounted, is connected to one horizontal branch 21^b of the cross 5^b and the cold water supply pipe 2^b in which the valve 4^b is mounted is connected to the oppositely disposed branch 22^b of the cross 5^b.

15 In order to provide for an ejector action in the inlet so as to control the manner of flow of the water as set forth specifically in connection with Figures 1 to 3, there is provided in the inlets to the connection 5^b restricted passages 16^b and 17^b whereby an ejector action is had insuring that the water will flow normally through the conduit 11^b to the spout.

20 In this modification of our invention as in the previous modifications considered, there is mounted in the spout a control valve similar to the valve 12. When this control valve is closed, the water is caused to pass upwardly through the conduit 11^b to the shower head. The ejector action provided by the restrictions 16^b and 17^b in this form of our invention illustrated in Figure 5 insures that the water will normally pass through the spout outlet and will not back up and flow from the shower head connected with the conduit 13^b.

25 Having fully described our invention, it is to be understood that we do not wish to be limited to the details herein set forth, but our invention is of the full scope of the appended claims.

We claim:

30 1. A combination fixture including an inlet and a pair of outlets, an orificed dividing plate within the fixture, a valved outlet member connected with one of said outlets, a valve mounted in the valved outlet member, the orifice member having a pair of orifices for controlling the flow to the outlets, one orifice being positioned between the 35 inlet and the valved outlet member, and the other orifice being positioned between the valved outlet and the other outlet.

3. In a combination spout and spray fixture, a hot water pipe, a cold water pipe, valves for controlling the flow of water in said pipes, a mixing member connected with the hot and cold water pipes, an orificed connecting member, a pipe connected with the inlet of the orificed connecting member and the mixing member, a valve spout connected with an outlet of the orificed connecting member, and a spray connected with a second outlet of the orificed connecting member, the orificed connecting member including an orificed plate having a pair of orifices, one for restricting the flow of water from the inlet to the spout outlet, and the other for controlling the flow of water from the inlet to the spray outlet, and a valve member mounted in the spout member. 5

4. In a combination spout and spray fixture, a connecting member having a single inlet and a pair of outlets, and an orificed plate having a pair of orifices positioned between the inlet and the outlets. 10

5. In a combination spout and spray fixture, a connecting member having a plurality of outlets and one or more inlets, with a restriction formed in one of said inlets so as to provide an ejector action when fluid is emitted through said inlet or inlets. 15

6. In a combination spout and spray fixture, a connecting member having a plurality of outlets, and an inlet provided with an ejector device. 20

7. In a combination spout and spray fixture, a connecting member having a plurality of outlets, and an inlet being provided with an ejector device. 25

8. In a combination spout and spray fixture, an elbow connecting member having an outlet in one branch of said elbow, and having an inlet and another outlet in the other branch of said elbow, said inlet being provided with an ejector device. 30

9. In combination spout and spray fixture, an elbow connecting member having vertical and horizontal branches, an outlet port formed in said horizontal branch, an inlet port and another outlet port formed in said vertical branch, and an ejector device provided in one of said ports. 35

10. In a combination spout and spray fixture, an elbow connecting member having an outlet port in one branch of said elbow, and having a pair of ports adjacent each other provided in the other branch of said elbow, each of said pair of ports having restricted passageways and adapted to be utilized interchangeably as inlet and outlet ports. 40
